U.S. Applications:

CLAIM

(62) Division of application No. 29/707,052, filed on Sep. 25, 2019, now Pat. No. Des. 914,076.

The ornamental design for a camera, as shown and described.

(51) **LOC (14) Cl. 16-05**

DESCRIPTION

(52) **U.S. Cl. USPC D16/219; D16/202**

FIG. 1 is a front perspective view of a camera in accordance with our new design;

(58) **Field of Classification Search**

FIG. 2 is a rear perspective view thereof;

USPC D16/200, 202, 203, 204, 205, 214, 218,
D16/219

FIG. 3 is a front elevation view thereof;

CPC H04N 23/50; H04N 23/51; H04N 23/54;
H04N 23/55; H04N 23/62; H04N 23/63

FIG. 4 is a rear elevation view thereof;

See application file for complete search history.

FIG. 5 is a left side elevation view thereof;

(56) **References Cited**

FIG. 6 is a right side elevation view thereof;

FIG. 7 is a top plan view thereof; and,

FIG. 8 is a bottom plan view thereof.

U.S. PATENT DOCUMENTS

The broken lines in the drawings depict portions of the camera that form no part of the claimed design.
